(57) **CLAIM**

The ornamental design for a shopping bag, as shown and described.

DESCRIPTION

FIG. 1 is a top front perspective view of a shopping bag, showing my new design;

FIG. 2 is a front elevation view thereof;

FIG. 3 is a rear elevation view thereof;

FIG. 4 is a right-side elevation view thereof, the left-side elevation view being a mirror image thereof;

FIG. 5 is a top plan view thereof;

FIG. 6 is a bottom plan view thereof;

FIG. 7 is a top rear perspective view thereof; and,

FIG. 8 is a top rear perspective view thereof, viewed from a higher elevation compared to FIG. 7.

The use of stippling indicates the contrasting appearance of hook and loop fasteners.
